YARN HOLDING MEANS

Ivan W. Grotthey, Laconia, N. H., assignor to
 Scott & Williams, Incorporated, Laconia, N. H.,
 a corporation of Massachusetts

Application August 18, 1943, Serial No. 499,141

15 Claims. (Cl. 66—125)

This invention relates to yarn feeding devices for presenting yarns to the needles of a knitting machine, and more particularly to such a control of the yarns as they leave the yarn packages, hereinafter referred to as cones, as will prevent the formation of so-called knots in the knitted fabric frequently present when high-twist yarns are used. As high-twist yarns leave the cones they have a tendency to form kinks that are not straightened out before they reach the fabric, as a consequence of which the kinks bunch up, having an appearance of knots, or slubs, as they are knitted into the fabric.

The present invention provides such a control over the yarns as they leave the cones on the way to the knitting machine that the formation of kinks in the yarn is virtually eliminated.

The formation of the knots or slubs frequently results from the stopping of the feeding of a high-twist yarn. The stopping of the feeding of the yarn allows slack to occur which permits the high-twist in the yarn to twist or kink the yarn in such a manner that any subsequent rubbing action and tension thereon in the knitting of the yarn will not cause the yarn to resume its previous condition.

In the drawings:

Fig. 1 is a fragmentary view showing a part of a knitting machine, a yarn cone feeding yarn to the needles of the knitting machine, and holding mechanism for maintaining the yarn in engagement with the yarn cone;

Fig. 2 is a perspective view showing a yarn cone and a modified form of yarn holder;

Fig. 3 is a plan view of the holder shown in Fig. 2; and

Fig. 4 is a fragmentary view showing another form of yarn tension usable in place of the disc tension of Fig. 1.

In the knitting of fabrics with high twist yarns it has been found that such yarns when led from a cone, such as 10, have a tendency to kink or coil, this being especially so when the feeding of the yarn is temporarily stopped or where, as in heel and toe knitting, the needle cylinder reciprocates. In either case, the cessation of the call for the yarn by the needles permits a looseness or slack to be formed in the yarn in the vicinity of the cone (allowing the yarn to kink or coil). Upon resumption of the call by the needles for the yarn, the kinks or slubs remain in the yarn and are knitted into the fabric, forming obvious imperfections. Passing the yarn between the discs of the usual disc tension does not overcome the formation of kinks or slubs

adjacent to the cone, but on the contrary, the tension exerted by such discs on the high twist yarn tends to increase the twist between the tension disc and the cone, aggravating or accelerating the tendency of the yarn to coil or kink.

It was found that the formation of slubs or kinks in the yarn could be virtually eliminated, especially such coils or kinks as result from the temporary non-feeding of the yarn, by holding the yarn lightly against the cone as it is being drawn off and as illustrated in the figures of the drawings.

The most effective way to control the yarn was found to flow from the use of feathers or threads as illustrated. The feathers or threads engage the yarn lightly and do not have the tendency of a disc tension to force the twist back toward the cone. In other words, the feathers or threads maintain the yarn leading from the cone in light contact therewith, thus preventing any looseness of the yarn akin to ballooning and the formation of kinks or coils in the yarn. Furthermore, the feathers or threads retain control of the yarn even in the event air currents tend to whip the yarn loose of the cone, such whipping inevitably resulting in the formation of kinks or coils in the yarn, which, when once formed, are not removed by passage of the yarn between the discs of the usual disc tension.

While a single cone only has been shown in the drawings, ordinarily a plurality of yarns is mounted on the usual bobbin stand of the machine to permit the interchangeable feeding of yarns or the simultaneous feeding of two or more yarns, as, for example, in plating.

With reference to Fig. 1 of the drawings, the knitting machine is shown as having a latch ring 1 past which the needles 2 rotate. At the throatplate 3 of the latch ring a yarn guide 4 is pivoted at 5 to a bracket 6 carried by the latch ring. The single yarn guide 4 has been shown by way of example, a plurality of yarn guides being customarily mounted in the latch ring.

Mounted upon a bracket 7, carried by the machine frame, is a can or receptacle 8 within which is carried a smaller can or receptacle 9. Within the latter is mounted a yarn cone 10 which rests upon a felt or other cushion 11. Circumferentially spaced around the can 8 are blocks 12 (four in this instance), each block being provided with a vertically extending hole in which bent rods 13 are adjustably seated for vertical or pivotal adjustments, set-screws 14 retaining the rods in adjusted position.

Detachably connected to the rods 13 at their upper ends are tubes 15, wires 16 being soldered, or otherwise secured, thereto and serving as connecting links between the rods 13 and the tubes 15. Seated in the other end of each tube 15 is a feather 17, the stem of which may be secured in any desired manner in its tube 15. The feathers 17 rest lightly edgewise on the cone of yarn 10, coming in contact with the yarn as the yarn is drawn off the cone by the needles 2. The feathers are biased to hold the yarn against the cone. As shown at the left of Fig. 1, each feather assembly—the pin or wire 16 of which pivots in the end of its rod 13—may be moved to the dotted line position shown in Fig. 1 and when released will fall by gravity against the cone, as illustrated in the full-line position at the left of Fig. 1.

Yarn Y after leaving the cone 10 may pass through the eyes 18 of a bracket 19 connected to an upright 20, which is supported from a convenient part of the machine frame. Carried by the bracket 19 is a disc tension 21, between the opposed discs of which the yarn Y passes. From the upper eye in the bracket 19 the yarn may pass through other guide eyes carried by another bracket 22 supported by upright 20 (and from there extending downwardly) through an eye of a third bracket 23 carried by the latch ring 1. The yarn Y may then pass through yarn guide eyes 24 of the yarn lever 4 and to the needles, as shown. It is desirable that the yarn tension 21 be located as close to the yarn guides as possible.

For the purposes of illustration, but without limiting the invention, four feather assemblies have been shown equally spaced around the cone 10. It is desirable, however, that the feathers contacting the cone be sufficient in number and length as to engage substantially the entire circumference of the cone when full. As yarn is drawn off the cone and the diameter thereof decreases, the feathers move gradually to remain in contact with the cone surface, the necessary movement of the feathers to remain in contact with the cone being assisted by the angular disposition of each tube 15 with respect to its supporting rod 13 as well as by the weight of the tube. The edges of the feathers preferably are cut to a curve to follow the contour of the cone 10 so as to insure proper contact therewith.

In Figs. 2 and 3 there is shown a modified form of yarn holder. The can 9 adjustably supports the rods or uprights 13 in the same manner as shown in Fig. 1. Also the tubes 15 and attached wires 16 are pivotally mounted in the rods 13 in the same manner as shown in Fig. 1.

The feathers shown in Fig. 1 illustrate one form or means for accomplishing the desired purpose. Any yielding material to which the yarn Y will not adhere, and which will maintain the yarn Y in light engagement with the cone may be used as a substitute for the feathers. As an example, there are shown in Figs. 2 and 3 threads or yarns 25 which engage the yarn Y to hold the same in engagement with the cone. The threads 25 are attached at each end to eyelets 26 formed in a curved wire support 27, one end of which is secured in a tube 15.

In Figs. 2 and 3 four wires 27 are shown, said wires being spaced apart about 90°. The number four (4) is illustrative; in some instances three would be sufficient for the purpose, namely, to effect a complete circumferential coverage of the

cone by the threads or yarns 25 to the end that there shall be no escape for yarn Y between adjacent threads 25.

In Fig. 1 the tubes 15 are shown as at an angle 5 to the upper, bent ends of rods 13, whereas in Fig. 2 the tubes 15 are shown as straight prolongations of the rods 13. In either case the upper ends of rods 13 are inclined to the vertical and the rods are adjustably mounted in the blocks 10 12, an arrangement which so positions the pivots of the feathers 17 or threads 24 as to cause the weight of the parts pivotally carried by the rods 13 to swing and maintain the feathers or threads in engagement with yarn Y leading from the cone.

In Fig. 4 is shown a yarn tension that can be acceptably employed in place of the disc tension of Fig. 1. The tension of Fig. 4, generally indicated by the numeral 28, can be attached to any 20 convenient part of the bobbin stand bracket carried by the knitting machine. The tension 28 comprises a plurality of bars or studs 29 (two being shown) carried by a bracket 30 forming part of the tension 28. A wire or rod 31 having eyes 32 through which the yarn Y passes is pivotally supported in the bracket 30. As shown in Fig. 4, the yarn passes through an eyelet 32 around a stud 29, through another eyelet 32, around a second stud 29 and finally through another eyelet 32. The normal position of the eyelets 32 with respect to the studs 29 is illustrated in Fig. 4, said eyelets being retained in the position shown by means of a light spring 33, one end of which is attached to an eyelet, the other 35 end being connected to the bracket 30 as shown. The relative positions of the eyelets 32 and studs 29 impose a tortuous-course tension upon the yarn Y which is constantly variable, while the machine is knitting, by reason of the pivotal mounting of the wire or rod 31. In other words, the constant variations in the pull upon the yarn Y incidental to knots, slubs and other causes is accommodated by the vibration of the eyelets 32 to and from the position shown in Fig. 4 to and 40 from a position more nearly in line with the studs 29. It is desirable that the yarn tension 28 be located as close to the yarn guides as possible.

Whereas neither the yarn tension 21 of Fig. 1 50 nor the yarn tension 28 of Fig. 4, when acting alone, will serve the purpose of the present invention, each may be used, as illustrated, in conjunction with the yarn-holding feathers in Fig. 1 or the threads 25 of Figs. 2 and 3. When combined, the normal knitting tension, either by the disc tension of Fig. 1 or the tension of Fig. 4, is lightened to some extent; however, such yarn tensions impose most of the so-called knitting tensions upon the yarns to the end that the latter shall be fed to the needles of the knitting machine under a normal knitting tension. In other words, the primary function of the yarn-holding feathers 17, threads 25, or equivalent means, is to retain the yarn Y in engagement with the cone as the said yarn is being withdrawn therefrom by the call of the needles knitting the same.

In the preceding description specific means for retaining the yarn Y in engagement with the cone 70 have been described and two forms of yarn tension acting in conjunction with the yarn holding means have also been described. The specific illustrations have been referred to for illustrative purposes only, without limiting the invention otherwise than as defined by the appended claims.

I claim:

1. In combination with a yarn cone stand, yarn holder supporting means carried by said stand and yarn holding means carried by the said supporting means, said yarn holding means including a flexible element for engagement with the yarn on the cone to exert a light drag upon the yarn in its passage from the cone, the engagement of the yarn by the flexible element being such as to prevent a kinking of the yarn as it is drawn from the cone.

2. A yarn holder for knitting machines comprising a plurality of yarn engaging means and means pivotally supporting said yarn engaging means, said yarn engaging means being constructed and arranged to collectively encircle a yarn cone and biased to hold against the cone the yarn being drawn from the cone.

3. A yarn holder for knitting machines comprising a plurality of flexible yarn engaging means adapted to collectively encircle a yarn cone and means pivotally supporting said yarn engaging means, said yarn engaging means and their supporting means being so angularly related said yarn engaging means are biased for engagement with the yarn being drawn from the cone.

4. A yarn holder for knitting machines comprising a plurality of yarn engaging means adapted to extend about a yarn cone and means pivotally supporting said yarn engaging means, each yarn engaging means and its supporting means being so angularly related said yarn engaging means is biased to engage the yarn cone.

5. A yarn holder comprising supporting means adapted to extend about a yarn cone, spaced rods projecting from said supporting means and flexible yarn engaging means pivotally mounted on said rods and biased to hold against the cone, the yarn being drawn therefrom.

6. A yarn holder comprising supporting means adapted to extend about a yarn cone, rods projecting from said supporting means in a circle about the yarn cone and yarn engaging means pivotally mounted on said rods and projecting therefrom, said rods and yarn engaging means having an angular relation biasing said yarn engaging means for engagement with the cone.

7. A yarn holding device for the yarn cones of knitting machines comprising a circular support, a plurality of spaced rods circumferentially disposed around the support and extending upwardly therefrom, feather yarn engaging elements pivotally carried by the upper ends of the rods, the pivotal mounting of the yarn engaging elements being such as to cause said elements to swing to a position against the yarn on a cone.

8. A yarn holding device for the yarn cones of knitting machines comprising a circular support, a plurality of upwardly projecting spaced rods carried by said support and feather yarn engaging elements pivotally mounted on the upper ends of said rods and collectively encircling the cone, said yarn engaging elements being biased to engage the yarn on the cone.

9. A yarn holding device for the yarn cones of knitting machines comprising a circular support, a plurality of spaced upwardly projecting rods having inwardly inclined upper portions

carried by said support and feather yarn engaging elements pivotally mounted on the upper ends of said rods, said yarn engaging elements being angularly disposed with respect to the inclined upper portions of said rods for biasing said elements to engage the cone.

10. A yarn holding assembly for acting upon yarns to be fed to a knitting machine, said assembly including a seat for a yarn cone, a support, rods mounted in said support for vertical and pivotal adjustments, tubes pivotally supported in the upper ends of the rods and angularly disposed with respect thereto, the pivotal support for each tube including a pin connected thereto and projecting from one end thereof and a feather fixedly mounted in the other end of each tube, the angular and pivotal mounting of each tube and connected feather permitting the feather to swing to and from the cone, and when released to gravitate into engagement with the cone.

11. A yarn holding device for the yarn cones of knitting machines comprising a circular support, a plurality of spaced upwardly projecting rods carried by said support and flexible threadlike yarn engaging elements pivotally mounted on the upper ends of said rod, said yarn engaging elements being angularly disposed with respect to said rods for biasing said elements to engage the cone.

12. A yarn holding device for the yarn cones of knitting machines comprising a circular support, a plurality of spaced vertically arranged rods carried thereby, carrier members pivotally mounted on said rods and angularly disposed with respect thereto, and flexible threadlike yarn engaging elements connecting spaced points on said carrier members, the pivotal mounting of said carrier members being constructed and arranged to engage the yarn engaging elements with the cone.

13. A yarn holding device for the yarn cones of knitting machines comprising a circular support, a plurality of spaced vertically arranged rods carried thereby, carrier members pivotally mounted on said rods, and flexible threadlike yarn engaging elements connecting spaced points on said carrier members and spaced from said carrier members between said spaced points, said carrier members being angularly disposed with respect to said rods to bias said carrier members to engage said yarn engaging elements with the cone.

14. A yarn holding device for the yarn cones of knitting machines comprising a circular support, a plurality of spaced vertically arranged rods carried thereby, curved carrier members pivotally mounted on said rods and flexible threadlike yarn engaging elements connecting spaced points on said carrier members, said carrier members being so angularly disposed with respect to said rods as to bias said carrier members for movement engaging said elements with said cone.

15. In a knitting machine, a cone having a yarn supply thereon for the machine needles, means for tensioning said yarn in its passage to the needles and yarn engaging means constructed and arranged to move bodily towards the cone to hold the yarn being drawn from the cone against the yarn on the cone as the diameter of the cone decreases.

IVAN W. GROTHEY.
